UNITED STATES PATENT OFFICE.

HERMAN G. LIEBENTHAL, OF PHILADELPHIA, PENNSYLVANIA.

DUPLICATING-MACHINE.

1,085,618.

Specification of Letters Patent.

Patented Feb. 3, 1914.

Application filed September 23, 1913. Serial No. 791,321.

To all whom it may concern:

Be it known that I, HERMAN G. LIEBENTHAL, a citizen of the United States, residing at Philadelphia, in the State of Pennsylvania, have invented a certain new and useful Improvement in Duplicating-Machines, whereof the following is a specification, reference being had to the accompanying drawings.

10 My improvement is particularly applicable to printing machines of the type known commercially as the "Multigraph" comprising a rotary printing cylinder having a series of undercut channels in its periphery extending parallel with its axis to receive complementary shaped flanged type which said cylinder presents in opposition to the other member of the printing couple. As ordinarily constructed, the printed impressions from such a machine are irregular in accordance with the length of the lines of type; because the lines of type extend parallel with the axis of the printing cylinder and are successively pressed between the 15 printing couple with a given pressure which, being the same for each line, is variable per unit of length of the line. For instance, a line one-half the length of the cylinder would be printed with a pressure, per unit 20 of length of that line, double the pressure per unit of length of a line which is the full length of the cylinder, and consequently the shorter the lines the more deeply and darkly they are printed.

25 Therefore, it is the object of my invention to provide such a machine with means to equalize the pressure per unit of area upon the successive lines of type in compensation for variations in the length of the lines; so 30 that the printed impressions made from successive lines shall be uniform in depth and darkness regardless of differences in the length of said lines.

35 My invention provides "make-ready" devices adapted to be used in connection with the successive lines of type to sustain a portion of the pressure in the regions of the line which otherwise would be blank, and, as hereinafter described, such devices include filling blocks which fit in the type 40 channels in said cylinder and support surface strips adapted to extend in alinement with the type faces and between the inking ribbon and the platen; each of said strips 45 having tips, at one end, fitting in sockets in a band extending circumferentially on said

drum, by which said strips are supported in proper relation with the lines of type; the opposite end of each strip having a lug with flanges engaged by the overhanging ledges 50 in said channel; said strip having means to prevent its longitudinal movement and escape from said band, including a wedge abutment fitted in the channel against the strip lug.

55 My invention comprises the various novel features of construction and arrangement hereinafter more definitely specified.

60 In the drawings; Figure I is a vertical transverse sectional view of a duplicating machine including a rotary printing cylinder and rotary platen, and embodying my invention; section being taken on the line I, I in Fig. II. Fig. II is a fragmentary inverted plan view of a portion of said cylinder, with letter type and an embodiment of my invention set therein. Fig. III is a fragmentary longitudinal sectional view taken on the line III, III in Figs. I and II. Fig. IV is a fragmentary transverse 65 sectional view taken on the line IV, IV in Figs. II and III. Fig. V is a fragmentary transverse sectional view taken on the line V, V in Figs. II and III. Fig. VI is a fragmentary transverse sectional view taken 70 on the line VI, VI in Figs. II and III. Fig. VII is a plan view of the surface strip shown at the upper portion of Fig. II. Fig. VIII is a side elevation of a filling block such as shown in Figs. II and V. Fig. IX 75 is an end view of said filling block. Fig. X is an end view of one of the sheet metal wedge abutments shown in Figs. II and III. Fig. XI is a vertical transverse sectional view of the printing cylinder of a modified 80 form of duplicating machine, showing a modified form of my invention. Fig. XII is a fragmentary front elevation of the cylinder shown in Fig. XI.

85 In said figures; 1 indicates the frame of a multigraph machine having bearings 2 and 3 for the shaft 5 of the rotary printing drum 6 having the curved surface 8 with the undercut channels 9 therein. Said drum 100 6 is conveniently provided with means for moving said surface 8 about its center of curvature, including the handle 11 rigidly connected with said shaft 5.

105 The platen shaft 13 being journaled in said frame 1 has the gear 14 engaging the gear 15 of said drum 6 and carries the cylindrical platen roller 17 having the face

18 of resilient material, conveniently rubber, extending with its axis parallel with the axis of said drum; so that when said drum is turned by the handle 11, said platen roller 5 is turned at the same surface speed. Said platen roller shaft 13 is so journaled that it may be adjusted toward and away from said drum shaft 5, but the means for effecting such adjustments are well known and therefore are not illustrated. Such adjustment is used to vary the printing pressure between the resilient surface 18 of said platen roller 17 and the printing faces of the type 20 which, as shown in Figs. I, IV and V, have 10 flanges 21, fitting said undercut channels 9 in the curved face 8 of said drum 6. Such variation in the printing pressure is effected to vary the depth of the impression of the printing faces of said type 20 with respect 15 to the paper 22, through the inking ribbon 23 which is interposed between said paper and said type faces as shown in Fig. I. In order to equalize the pressure per unit of area upon the successive lines of said 20 printing type 20 in compensation for variations in the length of said lines, I interpose between said curved surface 8 of the drum 6 and the opposed surface 18 of the platen 17 a cam element or elements carried by said 25 drum at its surface 8, preferably including several different patterns of surface strips, as hereinafter described.

As indicated in Fig. II, the date, the title "—Notice—" and the salutation "Dear 30 sir:—" compose three separate lines set in successive channels in the printing drum 6 and extending only a small fraction of the length of said drum. Consequently, unless 35 means are provided to equalize the pressure per unit of length of the lines, said short lines will be much more deeply and darkly 40 printed than the succeeding lines which are of greater length; because the whole pressure between the printing couple is borne by 45 each line in succession as it is brought, by rotation of the printing drum, to a position normal to both axes of the printing couple; the inking ribbon 23, which is carried by said drum 6 extending between the spools 50 25 over the type face, between said faces and said platen, being pressed into the paper 22 more or less deeply in accordance with the pressure per unit of length of the line which 55 is being printed. Therefore, I provide means to bear a portion of the pressure at the ends of the short lines so as to lessen the pressure upon the type faces composing such lines. Such means includes the filling blocks 27 conveniently formed of cast metal having 60 flanges 28 complementary to and fitted in said channels 9 like the flanges 21 of the type 20 aforesaid. Said blocks have their heads 29 eccentrically disposed with respect to their webs 30, as shown in Figs. V and IX 65 so as to support the surface strips 31, 32 and

33, as shown in Fig. II; said strips extending radially beyond the printing surface of the type 20 and over-lying the inking ribbon 23, so as to be interposed between the latter and the paper 22 where the latter extends over the platen surface 18. It is to be noted that a strip similar to the strip 32 aforesaid, having filling blocks 27 to support it, may be employed at the lower end of the letter composition, the upper end of which is shown in Fig. II, such additional strip 32 bearing a portion of the pressure at the end of the short lines formed by "Yours truly" or similar composition preceding the signature. Moreover if the signature is that of a person having a title such as "manager" an additional strip 33, with suitable filling blocks 27 supporting it, is employed to bear a portion of the pressure at the ends of that line. Each of said strips has a pair of tips 34 at one end thereof fitting in adjoining sockets 35 in the band 36, as best shown in Fig. II; said sockets 35 being respectively in alinement with the channels 9 in said drum, said band being flexible and resilient 45 and fitted to the sectoral cylindrical surface of said drum, as shown in Fig. III, and having at one end the flexible hook 38 overhanging the end of said surface and engaging one of the guide rods 39, over which said ribbon 23 extends, as shown in Fig. I. Said band 36 may have such hooks at each end, but I prefer to provide the opposite end of said band with a rigid hook such as shown at 40 in Fig. II, extending laterally from the band and engaging in the recess 41 of the undercut abutment 42 which is conveniently secured to said drum 6 by the screw 43. Each of said strips 31, 32 and 33 has at its end opposite said tips 34 a lug 45 including 50 a web fitted to extend in one of said channels 9 and having flanges 46 engaged by the overhanging ledges in said channel. I provide means to prevent longitudinal movement of said strips and their escape from 55 said band, including resilient sheet metal abutments 48 which, as shown in Fig. X, have flanges 49 adapted to be engaged by the overhanging ledges in said channels 9 and, as shown in Fig. II, said wedge abutments 60 are respectively fitted against said strip lugs 45 in said channels.

The form of my invention shown in Figs. XI and XII differs from that above described only as to the specific details of construction of the flexible, sectoral, cylindrical band 52 which is of greater circumferential extent than the band 36 above described, so as to be coextensive with the sectoral cylindrical curved surface 53 of the drum 54 125 which has a plurality of undercut channels 55 in its periphery similar to the channels 9 above described. Said band 52 has notches 56 respectively in alinement with said channels 55 to receive the tips of the surface 130

strips 31, 32 and 33 above described but has hooks at its opposite ends differing in construction and arrangement from the hooks with which said band 36 is provided. Referring to Fig. XI it may be observed that the flexible hook 58 which is secured to the end of said band 52 by the rivet 59 overhangs and engages one end of said sectoral surface 53. As shown in Fig. XII, the hook

5 10 15 20 25 30 35 40 45 50 55 60 65 70 75 80 85 90 95 100 105 110 115 120 125 130

hook 61 at the opposite end of said band 52 projects laterally like the hook 40 above described but has at the distal end thereof the flange 62 engaging the undercut abutment formed by the end rail 63 of the series which form the channels 55 between them.

Although I find it convenient to form the sockets in said bands 36 and 52 by milling notches in the peripheries thereof parallel with the axis of the drum and covering said

20 notches with respective sheet metal strips 65 and 66 set in the perimeters of said bands, as respectively indicated in Figs. II and XII, and attached thereto only at the ends; it is to be understood that sockets capable 25 of holding the tips 35 of said surface strips may be formed by undercutting the notches in said bands, without the use of said cover strips. Moreover, it is to be understood that said strips may be otherwise held than 30 by a tip or tips at one end and a lug at the other. For instance, said strips may be provided with tips at both ends fitted to respective bands extending circumferentially on the drum, or, said strips may be provided at 35 each end with resilient sheet metal wedges, similar to the abutments 48 but directly connected with said strips, and such retaining means may be in unitary relation with the respective strips.

40 I do not desire to limit myself to the precise details of construction and arrangement herein set forth, as it is obvious that various modifications may be made therein without departing from the essential features of my 45 invention as defined in the appended claims.

I claim:—

1. In a duplicating machine, the combination with a rotary cylindrical platen; of a rotary printing drum having a sectoral, cylindrically curved, surface with a plurality of undercut channels in its periphery, and an undercut abutment at one end thereof; a flexible sectoral cylindrical band extending circumferentially on said drum, having 55 sockets in alinement with said channels, and means securing it in stationary relation with said drum including a flexible hook at one end overhanging and engaging one end of said sectoral surface, and a rigid hook, at 60 the other end, engaging said abutment; type having flanges fitted in said channels; an inking ribbon interposed between the type faces and said platen; filling blocks having webs and flanges fitted in said channels, and heads eccentric to said webs exterior to said

channels; surface strips supported by said filling blocks adapted to extend in alinement with the type faces between the inking ribbon and the platen; said strips being of different patterns, having recesses for short lines of type at respectively different regions of their length; whereby a portion of the printing pressure is borne by said strips; a pair of tips at one end of each of said strips fitting adjoining sockets in said band; a lug at the other end of each of said strips, fitted to extend in one of said channels and having flanges engaged by the overhanging ledges in said channel; and means arranged to prevent longitudinal movement of said strips and their escape from said band, including resilient sheet metal wedge abutments respectively fitted against said strip lugs in said channels.

2. In a duplicating machine, the combination with a rotary cylindrical platen; of a rotary printing drum having a sectoral surface with a plurality of undercut channels in its periphery, and an undercut abutment at one end thereof; a flexible sectoral cylindrical band extending circumferentially on said drum, having sockets in alinement with said channels, and means securing it in stationary relation with said drum including a flexible hook at one end overhanging and engaging one end of said sectoral surface, and a rigid hook, at the other end, engaging said abutment; type having flanges fitted in said channels; an inking ribbon interposed between the type faces and said platen; filling blocks having webs and flanges fitted in said channels, and heads exterior to said channels; surface strips, supported by said filling blocks, adapted to extend in alinement with the type faces between the inking ribbon and the platen; said strips being of different patterns, having recesses for short lines of type at respectively different regions of their length; whereby a portion of the printing pressure is borne by said strips; a pair of tips at one end of each of said strips fitting adjoining sockets in said band; a lug at the other end of each of said strips, fitted to extend in one of said channels and having flanges engaged by the overhanging ledges in said channel; and means arranged to prevent longitudinal movement of said strips and their escape from said band, including wedge abutments respectively fitted against said strip lugs in said channels.

3. In a duplicating machine, the combination with a rotary cylindrical platen; of a rotary printing drum having a sectoral surface with a plurality of undercut channels in its periphery, and an undercut abutment at one end thereof; a flexible sectoral cylindrical band extending circumferentially on said drum, having sockets in alinement with said channels, and means securing

4
ing it in stationary relation with said drum including a flexible hook at one end overhanging and engaging one end of said sectoral surface, and a rigid hook, at the other 5 end, engaging said abutment; type having flanges fitted in said channels; an inking ribbon interposed between the type faces and said platen; filling blocks fitted in said channels; surface strips, supported by said 10 filling blocks, adapted to extend in alinement with the type faces between the inking ribbon and the platen; said strips being of different patterns, having recesses for short lines of type at respectively different regions 15 of their length; whereby a portion of the printing pressure is borne by said strips; a tip at one end of each of said strips fitting a socket in said band; a lug at the other end of each of said strips, fitted to extend in 20 one of said channels and having flanges engaged by the overhanging ledges in said channel; and means arranged to prevent longitudinal movement of said strips and their escape from said band, including abutments 25 respectively fitted against said strip lugs in said channels.

4. In a duplicating machine, the combination with a rotary cylindrical platen; of a rotary printing drum having a curved 30 surface with a plurality of undercut channels in its periphery; a sectoral cylindrical band extending circumferentially on said drum, having sockets in alinement with said channels, and means securing it in stationary relation with said drum including hooks 35 at each end; type having flanges fitted in said channels; and inking ribbon interposed between the type faces and said platen; filling blocks fitted in said channels; surface strips, supported by said filling blocks, 40 adapted to extend in alinement with the type faces between the inking ribbon and the platen; said strips being of different patterns, having recesses for short lines of type 45 at respectively different regions of their length; whereby a portion of the printing pressure is borne by said strips; a tip at one end of each of said strips fitting a socket in said band; a lug at the other end of each of said 50 strips, fitted to extend in one of said channels and having flanges engaged by the overhanging ledges in said channel; and means arranged to prevent longitudinal movement of said strips and their escape from said band, including wedge abutments 55 from said band, including abutments respectively fitted against said strip lugs in said channels.

5. In a duplicating machine, the combination with a rotary cylindrical platen; of a 60 rotary printing drum having a curved surface with a plurality of undercut channels in its periphery; a band extending circumferentially on said drum, having sockets in alinement with said channels, and means securing it in stationary relation with said 65

drum including hooks at each end; type having flanges fitted in said channels; an inking ribbon interposed between the type faces and said platen; filling blocks fitted in said channels; surface strips supported by 70 said filling blocks adapted to extend in alinement with the type faces between the inking ribbon and the platen; said strips being of different patterns, having recesses for short lines of type at respectively different 75 regions of their length; whereby a portion of the printing pressure is borne by said strip; a tip at one end of each of said strips fitting a socket in said band; a lug at the other end of each of said strips, fitted to extend in one of said channels and having flanges engaged by the overhanging ledges in said channel; and means arranged to prevent longitudinal movement of said strips and their escape from said band, including 80 abutments respectively fitted against said strip lugs in said channels.

6. In a duplicating machine, the combination with a rotary cylindrical platen; of a rotary printing drum having a curved surface with a plurality of undercut channels in its periphery; a band extending circumferentially on said drum, having sockets in alinement with said channels, and means securing it in stationary relation with said 90 drum; type having flanges fitted in said channels; an inking ribbon interposed between the type faces and said platen; filling blocks fitted in said channels; surface strips supported by said filling blocks adapted 95 to extend in alinement with the type faces between the inking ribbon and the platen; said strips being of different patterns, having recesses for short lines of type at respectively different regions of their length; whereby a portion of the printing pressure is borne by said strips; a tip at one end of each of said strips fitting a socket in said band; a lug at the other end of each of said strips, fitted to extend in one of said channels and having flanges engaged by the overhanging ledges in said channel; and means arranged to prevent longitudinal movement of said strips and their escape from said band, including abutments respectively fitted 100 against said strip lugs in said channels.

7. In a duplicating machine, the combination with a rotary cylindrical platen; of a rotary printing drum having a curved surface with a plurality of undercut channels in its periphery; a band extending circumferentially on said drum, having sockets in alinement with said channels, and means securing it in stationary relation with said 110 drum; type having flanges fitted in said channels; an inking ribbon interposed between the type faces and said platen; filling blocks fitted in said channels; surface strips supported by said filling blocks adapted 115 to extend in alinement with the type faces be- 120

125

- between the inking ribbon and the platen; whereby a portion of the printing pressure is borne by said strips; a tip at one end of each of said strips fitting a socket in said band; a lug at the other end of each of said strips, fitted to extend in one of said channels and having flanges engaged by the overhanging ledges in said channel; and means arranged to prevent longitudinal movement of said strips and their escape from said band, including abutments respectively fitted against said strip lugs in said channels.

8. In a duplicating machine, the combination with a platen; of a member having a curved surface with a plurality of undercut channels in its periphery; a circumferential series of sockets on said drum, in alinement with said channels; type having flanges fitted in said channels; an inking ribbon interposed between the type faces and said platen; filling blocks fitted in said channels; surface strips, supported by said filling blocks, adapted to extend in alinement with the type faces between the inking ribbon and the platen; whereby a portion of the printing pressure is borne by said strips; a tip at one end of each of said strips fitting said sockets; a lug at the other end of each of said strips, fitted to extend in one of said channels and having flanges engaged by the overhanging ledges in said channel; and means arranged to prevent longitudinal movement of said strips and their escape from said band.

9. In a duplicating machine, the combination with a platen; of a member having a curved surface with a plurality of undercut channels in its periphery; a circumferential series of sockets on said drum, in alinement with said channels; type having flanges fitted in said channels; an inking ribbon interposed between the type faces and said platen; filling blocks fitted in said channels; surface strips, supported by said filling blocks, adapted to extend in alinement with the type faces between the inking ribbon and the platen; whereby a portion of the printing pressure is borne by said strips; a tip at one end of each of said strips fitting said sockets; a lug at the other end of each of said strips, fitted to extend in one of said channels; and means arranged to prevent longitudinal movement of said strips and their escape from said band.

10. In a duplicating machine, the combination with a platen; of a member having a curved surface with a plurality of undercut channels in its periphery; a circumferential series of sockets on said drum, in alinement with said channels; type having flanges fitted in said channels; an inking ribbon interposed between the type faces and said platen; filling blocks fitted in said channels; surface strips, supported by said filling blocks, adapted to extend in alinement with the type faces between the inking ribbon and the platen; whereby a portion of the printing pressure is borne by said strips; a tip at one end of each of said strips fitting said sockets; a lug at the other end of each of said strips, fitted to extend in one of said channels; and means arranged to prevent longitudinal movement of said strips and their escape from said band.

11. In a duplicating machine, the combination with a platen; of a type holding member having a plurality of type channels in its surface; sockets on said member in alinement with said channels; type fitted in said channels; an inking ribbon, carried by said member, interposed between the type faces and said platen; filling blocks fitted in said channels; and surface strips, fitted to said sockets and separable from but supported by said filling blocks, adapted to extend in alinement with the type faces between said inking ribbon and platen; whereby a portion of the printing pressure is borne by said strips.

12. In a duplicating machine, the combination with a platen; of a type holding member having a plurality of type channels in its surface; sockets on said member in alinement with said channels; type fitted in said channels; filling blocks fitted in said channels; and surface strips, fitted to said sockets and supported by said filling blocks, adapted to extend in alinement with the type faces between said type and platen; whereby a portion of the printing pressure is borne by said strips.

13. In a duplicating machine, the combination with a platen; of a type holding member; type on said member; an inking ribbon, carried by said member, interposed between the type faces and said platen; a filling block on said member; and a surface strip, having means detachably connecting it with said member, independently of said block, but supported by said block, adapted to extend in alinement with the type faces between the inking ribbon and the platen; whereby a portion of the printing pressure is borne by said strip.

14. In a duplicating machine, the combination with a rotary printing drum having a plurality of undercut type channels in its periphery; of a separable band extending circumferentially on said drum, having sockets in alinement with said channels; a filling block fitted in one of said channels; and a surface strip having means to engage said sockets, independently of but supported by said block, adapted to extend in alinement with the type faces; whereby a portion of the printing pressure is borne by said strip.

15. In a duplicating machine, the combination with a rotary printing drum having a plurality of type channels in its periphery; of a band extending circumferentially on said drum, having sockets in alinement with

with said channels; a filling block fitted in one of said channels; and a surface strip having means to engage said sockets, independently of but supported by said block, adapted to extend in alinement with the type faces; whereby a portion of the printing pressure is borne by said strip.

16. In a duplicating machine, the combination with a rotary printing drum having means to hold type in lines; of a detachable band extending circumferentially on said drum, having sockets parallel with said lines; a filling block fitted to be set in said drum like a type; and a surface strip having means to engage said sockets, independently of but supported by said block, adapted to extend in alinement with the type faces; whereby a portion of the printing pressure is borne by said strip.

17. In a duplicating machine, the combination with a rotary printing drum having means to hold type in lines; of a band extending circumferentially on said drum, having sockets parallel with said lines; a filling block fitted to be set in said drum like a type; and a surface strip having means to engage said sockets, independently of but supported by said block, adapted to extend in alinement with the type faces; whereby a portion of the printing pressure is borne by said strip.

18. In a duplicating machine, the combination with a rotary printing drum having means to hold type in lines; of a band extending circumferentially on said drum, having sockets in alinement with said type; a filling block; and a surface strip having means to engage said sockets, independently of but supported by said block, adapted to extend in alinement with the type faces; whereby a portion of the printing pressure is borne by said strip.

19. In a duplicating machine, the combination with a type holding member; of means for lessening the pressure upon short lines of type therein, including surface strips of different patterns, having recesses for short lines of type at respectively different regions of their length, and means at their ends detachably connecting them with said type holding member.

20. In a duplicating machine, the combination with a type holding member; of means for lessening the pressure upon short lines of type therein, including surface strips having recesses for short lines of type at respectively different regions of their length, and means at their ends detachably connecting them with said type holding member.

21. In a duplicating machine, the combination with a type holding member; of means for lessening the pressure upon short lines of type therein, including surface strips having recesses for short lines of type

at respectively different regions of their length, and means detachably connecting them with said type holding member.

22. In a duplicating machine, the combination with a type holding member; of means for lessening the pressure upon short lines of type therein, including a surface strip having a recess for a short line of type, and means at its ends detachably connecting it with said type holding member.

23. In a duplicating machine, the combination with a type holding member; of means for lessening the pressure upon short lines of type therein, including a surface strip having a recess for a short line of type, and means detachably connecting it with said type holding member.

24. A surface strip adapted to extend in alinement with type faces in a type holding member and bear a portion of the printing pressure upon short lines of type in said member, having means arranged to detachably engage said member, including a pair of tips at one end and a flanged lug at the other end.

25. A surface strip adapted to extend in alinement with type faces in a type holding member and bear a portion of the printing pressure upon short lines of type in said member, having means arranged to detachably engage said member, including a tip at one end and a flanged lug at the other end.

26. A surface strip adapted to extend in alinement with type faces in a type holding member and bear a portion of the printing pressure upon short lines of type in said member, having means arranged to detachably engage said member, including a tip at one end and a lug at the other end.

27. An attachment for a printing drum, adapted to equalize the pressure upon long and short lines of type therein, including a flexible resilient band fitted to extend circumferentially on said drum and having hooks at its ends arranged to detachably engage said drum, surface strips adapted to extend on said drum over the faces of the type therein, parallel with the lines of type, each having means at one end arranged to detachably engage said band and having means at the other end arranged to detachably engage said drum independently of said band, and filling blocks arranged to be set in said drum to support said strips.

28. An attachment for a printing drum, adapted to equalize the pressure upon long and short lines of type therein, including a band fitted to extend circumferentially on said drum and having hooks at its ends arranged to detachably engage said drum, surface strips adapted to extend on said drum over the faces of the type therein, parallel with the lines of type, each having means at one end arranged to detachably engage said band and having means at the other end

arranged to detachably engage said drum independently of said band, and filling blocks arranged to be set in said drum to support said strips.

- 5 29. An attachment for a printing drum, adapted to equalize the pressure upon long and short lines of type therein, including a band fitted to extend circumferentially on said drum and having means arranged to detachably engage said drum, surface strips adapted to extend on said drum over the faces of the type therein, parallel with the lines of type, each having means at one end arranged to detachably engage said band

and having means at the other end arranged 15 to detachably engage said drum independently of said band, and filling blocks arranged to be set in said drum to support said strips.

In testimony whereof, I have hereunto 20 signed my name at Philadelphia, Pennsylvania, this nineteenth day of September, 1913.

HERMAN G. LIEBENTHAL.
